Primary Examiner — Kevin K Rudzinski(74) *Attorney, Agent, or Firm* — Dorsey & Whitney LLP(57) **CLAIM**

The ornamental design for a pocket for a medical scrub, as shown and described.

DESCRIPTION

FIG. 1 is a top, front, and right side perspective view of a pocket for a medical scrub, showing my new design.

FIG. 2 is a front elevation view thereof.

FIG. 3 is a back elevation view thereof.

FIG. 4 is a top plan view thereof.

FIG. 5 is a bottom plan view thereof.

FIG. 6 is a right side elevation view thereof, the left side elevation view is a mirror image.

FIG. 7 is a top, front, and right side perspective view thereof in an in use configuration; and,

FIG. 8 is a front elevation view thereof on a medical scrub. The broken lines showing environment of the pocket for a medical scrub form no part of the claimed design.

1 Claim, 4 Drawing Sheets(56)
